UNITED STATES PATENT OFFICE.

H. C. DREW, OF OSHAWA, CANADA WEST.

IMPROVEMENT IN WHEEL-VEHICLES.

Specification forming part of Letters Patent No. 40,025, dated September 22, 1863.

To all whom it may concern:

Be it known that I, H. C. DREW, of Oshawa, in the Province of Canada West, have invented certain new and useful Improvements in Wheel-Vehicles; and I do hereby declare that the following is a full, clear, and exact description of the same, reference being had to the accompanying drawings, making a part of this specification, in which—

Figure 1 is a side sectional view of my invention, taken in the line *x x*, Fig. 2. Fig. 2 is an inverted plan of the same. Fig. 3 is a front sectional view of the same, taken in the line *y y*, Fig. 2.

Similar letters of reference indicate corresponding parts in the several figures.

This invention relates to a novel arrangement of the front wheels and draft-pole thereof, whereby the wheels in passing over obstructions which may lie in their path are prevented from acting upon the draft-pole and moving the same laterally, as hitherto—a result which greatly fatigues the team.

To enable those skilled in the art to fully understand and construct my invention, I will proceed to describe it.

A represents the front and B the back axle-bed of a four-wheel vehicle; C, the reach or perch, the ends of which are permanently secured to the axle-beds, the front one, A, being fixed so as not to turn as hitherto. D D represent the back and D' D' the front wheels. These wheels are attached to separate or independent axles E, which are fitted loosely in proper bearings, *a*, underneath the axle-beds A B. The axles E are of slight taper form, and they are fitted quite loosely in their outer bearings, *a*. To the ends of both axle-beds A B there are attached friction-wheels F, which bear on the upper surfaces of the axles E and friction-wheels G, which are also attached to the ends of said beds, and bear against the back sides of the axles. These friction-wheels have their axes *b* attached to the ends of bent or right-angular heads H, which are secured to the ends of the beds, the wheels G being attached to the outer parts of the lower horizontal arms *c* of the heads H, and the wheels F, attached to the upper parts of the vertical arms *d* thereof. The wheels F diminish the friction produced by the weight of the load of the vehicle, while the wheels G diminish the

friction produced by the draft movement. The axles E are retained in proper position in their bearings by means of nuts *e* on their inner ends.

The axles E of the front wheels, D' D', are differently arranged from the back ones. The heads H are not attached permanently to the front axle-bed, but are secured thereto by vertical pivots *f*, which pass through ears or lugs *g* at the inner sides of the heads, and through the axle-bed A, as shown clearly in Fig. 3. This arrangement, it will be seen, admits of the heads working or turning horizontally on the pivots *f*. The inner bearings, *a*, also, of the axles of the front wheels, instead of being attached to the front axle-bed, A, are at the inner ends of metal bars I I, which are connected at their outer ends to the heads H by the pivots *f*, as shown clearly in Fig. 3, and as the friction-wheels F G of the front axle-bed are attached to the heads H thereof in the same way as the friction-wheels of the back axle-bed, it will be seen that the front wheels, D' D', and their axles E will be allowed to turn on the pivots *f* as centers, and the wheels F G have the same relative position with the front axles, E, at all points of their movement. The inner ends of the front axles, E, are fitted and work in segment-guides J, attached to the under side of the front axle-bed, A.

K is the draft-pole, which is attached by a link-joint, *g*, to the center of the front axle-bed, A. In the back part of the draft-pole K there is placed a bar, L, said bar being secured centrally in the draft-pole by a pivot, *h*, on which it is allowed to work freely. The ends of the bar L are connected by pivots *i i* to bars *j j*, the back ends of which are permanently attached to the bars I I near the pivots *f*.

By this arrangement it will be seen that a leverage-connection is formed between the draft-pole K and the front axles, E, and that the front wheels may be turned or "cramped" by a very slight lateral action of the team on the draft-pole, and the vehicle therefore readily turned. At the same time it will also be seen that there is a very slight leverage-power for wheels to act upon the draft-pole, as the pivots *f*, which are fulcrum-pins, are quite near wheels; consequently the wheels in passing over obstructions will not act upon the draft-pole and throw it violently to the right or left,

as is the case in ordinary wheel-vehicles. This is an important feature of the invention, and is a great relief to the team.

This invention is applicable to all kinds of wheel-vehicles, and its adoption will not add materially to the cost of construction.

I do not claim, broadly, the application of friction-wheels to the axles of wheel-vehicles to diminish friction in the running thereof; nor do I claim as new the idea of placing the wheels upon separate or divided and movable axles; but,

Having thus described my invention, what I do claim as new, and desire to secure by Letters Patent, is—

The combination of the segment-guides J J, pivoted bar L, and bars j j with the front axles and the tongue K, in the manner herein shown and described.

H. C. DREW.
